UNITED STATES PATENT OFFICE.

MILTON D. CAMPBELL, OF CINCINNATI, OHIO, ASSIGNOR TO THE PERKINS-CAMPBELL COMPANY, OF CINCINNATI, OHIO, A CORPORATION OF OHIO.

RADIATOR PROTECTOR.

Application filed May 15, 1924. Serial No. 713,613.

To all whom it may concern:

Be it known that I, MILTON D. CAMPBELL, a citizen of the United States, and a resident of Cincinnati, in the county of Hamilton and State of Ohio, have invented certain new and useful Improvements in Radiator Protectors, of which the following is a full, clear, and exact description, reference being had to the accompanying drawing, forming part of this specification.

My invention relates to radiator fronts formed of fabric, leather or other flexible material, together with a curtain, for exposure of desired portions of the radiator core.

There have been a considerable number of devices for protecting radiators against freezing and also keeping air from passing through the core in order to heat up the engines cooled by radiator water, in the automotive art.

It is my object to provide improvements in such devices, and more particularly to provide a curtain of panels connected to each other and slidably mounted so as to fall by gravity to the lower portion of the radiator cover, in a side-by-side relation.

It is my object to provide a device which is economical of construction and fully practical in its operation.

I accomplish my objects by that certain construction and arrangement of parts to be hereinafter more specifically pointed out and claimed.

In the drawing:

Figure 1 is a front elevation of the device.

Figure 2 is a side elevation thereof.

Figure 3 is a view like Figure 1 showing the curtain down.

Figure 4 is a section on the line 4—4 of Figure 3.

The radiator cover device is formed in the usual manner of a fabric piece 1 which may be buttoned to the front of the radiator as at 2, or may be formed with sides to engage around the sides of the radiator frame as at 3 (Figure 2). The front piece 1 covers the desired portion of the face of the radiator and has a central opening at 4 to expose the core of the radiator.

Mounted along the two vertical sides of the core opening are rods 5, 5, preferably of metal or fiber, having their ends 6 bent away slightly so as to elevate the main extent of the rods away from contact with

the piece 1. The ends of the rods may be riveted to the piece 1.

The shutter or curtain sections 7 are formed preferably of pieces of leather, fiber, metal or fabric of desired kind, stiffened so as to have little flexibility, and so as to act as rigid panels in operation. The curtain sections have flexible straps 8, connecting the inside top edge of each section with the inside top edge of the section below it. There are two rows of these straps in the form illustrated in the drawings, so that two flexible strips may be stitched to the tops of each section, instead of forming separate connecting strips for each panel of the curtain. The straps are secured to the piece at the bottom.

I have shown a central strap 9 extending vertically across the opening 4 in the piece 1, which has snap fastener buttons on it as at 10, and there will be a top snap fastener at 12, just above the middle of the opening 4.

The operator can then adjust the curtain to snap the fastener socket 13 at the center of the upper and outer curtain panel, over the topmost button 12, or any intermediate button on the central strap.

At the ends of each panel are mounted the sliders for engaging the two side rods. These sliders in the form shown have eyelets or rings 14 to engage over the rods, and shanks 15 to be riveted or otherwise secured to the center side edges of each curtain panel.

The panels are thus guided at all times on the rods, and can easily slide up and down on them. I preferably form the sliders as pieces of flat metal with a rubber cover thereon, although this is not essential.

When the curtain is down the panels arrange themselves with the upper one outermost, and the connecting straps bent up, as indicated at 8^a, in Figure 3, so as not to interfere with the panels lying side by side. When the upper panel is pulled up it will draw the next panel, and the next panel will draw up the panel below it, as is evident from the construction described.

For a remote control a cable 20 can be connected to the top panel, and run over a drum 21, mounted on the outer face of the instrument board or dash of the car. On the same spindle as the drum will be a drum 22 of much smaller diameter, and a pull cable 23 will be secured to this drum. The

pull cord will pass through a fitting into the inside of the dash or instrument board, and by a short pull will revolve the larger drum and bring the curtain to the desired height to cover the desired portion of the radiator.

I have shown a pulley 24 of the type used on window cords, which will catch the cable if pulled sidewise, or release it for moving in or out, by a pull to straight line with the pulley. This or some other device can be employed to lock the pull cord or cable to desired position.

The curtain will fall readily by gravity to its lower position when the pull cord is released.

It will be evident that my device can be inexpensively made, and installed without any difficulty on any automobile. The curtain panels and rods can be uniform for a large number of cars, and the pieces 1 or such other hoods as are used, can be easily mounted. There are no parts to rattle, as in a metal device, and the control by the operator is easy, while the covering of the desired portion of the radiator core can be easily and quickly accomplished.

It is quite practical to use a pull cord which is directly connected to the top curtain panel, without the drums.

Having thus described my invention, what I claim as new and desire to secure by Letters Patent, is:—

1. In combination with a flexible cover secured over a radiator front, and having an opening to expose the radiator core, rigid members extending lengthwise of the core and secured along the sides of the said opening, and a curtain having panels, straps connecting the tops of the panels to each other, and sliders on the panels engaging the rigid members, and means for holding the panels in relation extended over the opening in the cover.

2. In combination with a flexible cover secured over a radiator front, and having an opening to expose the radiator core, rigid members extending lengthwise of the core and secured along the sides of the said opening, and a curtain having panels secured successively at their tops by flexible members, and having sliders engaging the rigid members, and means for holding the panels in relation extended over the opening in the cover, said rigid members formed of rods secured in the cover above and below the opening, and the sliders being formed as rings to engage over the rods.

MILTON D. CAMPBELL.
